PILLOW

Harry L. Jacobson, 5232 Rexford Road, Philadelphia, Pa.

Filed Nov. 16, 1964, Ser. No. 82,612

Term of patent 14 years

(Cl. D3—9)

FIG. 1 is a perspective view of a pillow showing my new design.

FIG. 2 is a right side elevational view thereof, the left side elevation being exactly the same but opposite in direction.

FIG. 3 is a top plan view thereof.

FIG. 4 is a bottom plan view thereof.

FIG. 5 is a front elevational view thereof.

FIG. 6 is a rear elevational view thereof.

I claim:

The ornamental design for a pillow, as shown.
